UNITED STATES PATENT OFFICE.

JAY F. COLE AND EMIL W. PARNO, OF GREENE, IOWA.

ROOF-CONNECTION FOR RAILWAY-CARS.

SPECIFICATION forming part of Letters Patent No. 400,305, dated March 26, 1889.

Application filed December 3, 1888. Serial No. 292,572. (No model.)

To all whom it may concern:

Be it known that we, JAY F. COLE and EMIL W. PARNO, citizens of Greene, residing at Greene, in the county of Butler and State 5 of Iowa, have invented certain new and useful Improvements in Continuous Roofs for Railroad Coaches or Cars, of which the following is a description.

This invention relates to a device for closing the top portion of the opening between the ends of two adjoining cars; and it has for its object to provide means whereby cinders, smoke, dust, and the like coming from the engine over the roofs of the cars may be excluded from entrance thereto, and also serves as a means for excluding snow and rain from the platform.

The invention will be fully understood from the following description and claim, 20 when taken in connection with the accompanying drawings, in which—

Figure 1 is a side elevation of a portion of two adjoining cars, showing our improvements in position thereon. Fig. 2 is a view of one 25 section of the device removed from the car. Fig. 3 is a view of one of the brackets with a portion of one of the springs attached, showing the set-screw for securing the spring upon the bracket.

Referring by letter to the said drawings, A 30 indicate the sections of our improved device. These sections are each composed of parallel bars *a a*, which are curved somewhat longitudinally to conform to the curvature of the car-roof, and one of the bars of each section is adapted to be attached to the end of a car-roof over the platform by screws or other suitable fastening devices, so that when two cars have been brought together 35 40 the roof of the car will be extended, as it were, over the platform, and the sections brought to abut against each other, so as to exclude smoke and cinders or rain and snow.

Each of the bars *a* is provided on its inner side and at opposite points with brackets 45 B. These brackets (better shown in Fig. 3 of the drawings) have an attaching-flange provided with eyes for the reception of fastening devices and a lug, *b*. This lug *b*, which

is formed entire, is provided with an aperture, *c*, near its base or inner end, or at any suitable point, for the insertion of one end of the spiral or coiled springs D.

E indicates an internally-threaded aperture which leads through the rear of the 55 bracket into the aperture *c* of the lug *b*, and relatively at right angles thereto.

F indicates a set-screw in the threaded aperture E of the bracket. This set-screw is designed to impinge against the inserted end 60 of the spring in the aperture of the lug and securely hold the same in position.

By this construction it will be seen that the springs may be readily attached or removed and replaced by others should any of them 65 become impaired or injured. These springs serve to keep the frame expanded or extended, so that the sections are always in position to adjustably meet the sections of an adjoining or abutting car.

The bars *a* of each section are connected by a covering, which of necessity must be flexible, and this covering G should also be fire-proof, as well as water-proof.

The covering fabric may be applied or attached at opposite edges to the convex edges of the bars *a* by any suitable means, care being taken to make a tight joint. These devices are very effective in operation, and may be manufactured at a very small expense and 80 applied to cars without skilled labor.

Having described our invention, what we claim is—

In a car attachment such as described, the combination, with the parallel bars connected 85 by a flexible covering, of expanding springs connecting said bars, the brackets having a perforated lug adapted to receive the ends of the springs, and a perforated aperture communicating with the perforation in the lug, 90 and a set-screw adapted to engage the ends of the spring and secure the same in position, substantially as specified.

JAY F. COLE.
EMIL W. PARNO.
